UNITED STATES PATENT OFFICE.

CECIL O. PHILLIPS, OF NEW YORK, N. Y., ASSIGNOR TO THE AMERICAN COTTON OIL COMPANY, OF NEW YORK, N. Y., A CORPORATION OF NEW JERSEY.

METHOD AND APPARATUS FOR MOLDING SOAP.

1,391,972.

Specification of Letters Patent. Patented Sept. 27, 1921.

Application filed August 5, 1920. Serial No. 401,330.

To all whom it may concern:

Be it known that I, CECIL O. PHILLIPS, a citizen of the United States, residing at New York, in the county of New York, State of New York, have invented certain new and useful Improvements in Methods and Apparatus for Molding Soap; and I do hereby declare the following to be a full, clear, and exact description of the invention, such as will enable others skilled in the art to which it appertains to make and use the same.

This invention relates to an improved method and apparatus for the molding and cooling of molten soap, and the pressing of the resulting soap, whereby the molten soap is converted in a rapid and advantageous manner into the form of compressed cakes ready for packaging without further treatment.

According to the common methods of soap manufacture, the molten soap is poured into molds or frames, and is permitted to cool slowly. After cooling and solidifying, the soap is cut into slabs and bars, and subsequently pressed to produce the finished cake. These various operations require a very considerable time, and a large part of the ordinary soap factory is taken up with soap undergoing these various operations.

In my prior application, Serial No. 386,912, filed June 5, 1920, I have described an improved method and apparatus for molding and cooling molten soap and converting the soap into the form of solidified cakes in a rapid and advantageous manner.

The method and apparatus of the present invention are improvements on the method and apparatus of said prior application.

According to the present invention, the soap, while still molten, is charged into molds of the shape which it is desired to impart to the finished cake, and the molds are then passed through a cold, salt solution or brine where the soap is cooled without being brought into direct contact with the brine. During the cooling and molding operation, the soap cakes are subjected to a pressing operation, and this pressing operation is combined with the molding and cooling operations, so that the soap is directly converted into the form of the finished cakes without further manipulation, so that they may be directly wrapped and packed for shipment.

The improved apparatus of the present invention is generally similar to that of my aforesaid application, and comprises a receptacle for the brine used in the cooling of the soap, a series of molds arranged to receive the molten soap and to convey it through the cold brine while protecting the soap from direct contact with the brine, and pistons or plungers arranged to subject the soap in the molds to a pressing operation in order to give to the cakes of soap their final shape and appearance. It will be evident that the apparatus is capable of many variations in its specific construction, and that the improved process of the invention can likewise be carried out in various forms of apparatus provided the soap is subjected to the improved molding, cooling and pressing operations characteristic of the invention.

The invention involves various features of improvements both in the process and apparatus, which will more fully appear from the following more detailed description of the preferred embodiments thereof, and from the accompanying drawings, which illustrate in more or less conventional and diagrammatic manner the preferred embodiment of the apparatus of the invention, it being intended and understood that the invention is illustrated by, but is not limited to, the specific embodiments thereof specifically illustrated and described, and that variations and modifications can be made therein within the scope of the invention and the appended claims.

In the accompanying drawings:

Figure 1 is a view in elevation of one form of apparatus embodying the invention;

Fig. 2 is an enlarged view in sectional elevation of part of the apparatus of Fig. 1;

Fig. 3 is a similar view of another part of the apparatus of Fig. 1;

Fig. 4 is an enlarged sectional view of the filling mechanism taken on the line 4—4 of Fig. 1;

Fig. 5 is a detail view showing the construction of the mold sections;

Fig. 6 is a sectional view taken on line 6—6 of Fig. 2; and

Fig. 7 is an enlarged view showing part of the pressing mechanism.

In the apparatus illustrated in the accom-

panying drawings the tank for the cold salt solution or brine is indicated at 1, and is suitably supported by the supports 2 and 3, and by the shaft 4 which passes through 5 suitable stuffing boxes (not shown) in the side walls of the tank, and which shaft is in turn supported by bearings carried by the supports 5. The shaft 4 carries a spider or wheel 6 having the radially arranged outer 10 rim 7, which in turn supports the transverse arm 7^a carrying the mold sections 8. Each mold section has a series of three molds 9 of approximately the shape of the cake of soap to be produced, and in each 15 mold is a piston or a plunger 10 with piston rod 11 having a roller 12 at its outer end. The arrangement of the mold sections and molds is such that they form a cylindrical series of molds rotating upon the shaft 4. 20 Above the series of molds is the soap container 13 having steam jackets 14 for maintaining the soap at the proper temperature and preventing undue cooling thereof. The soap container is supported by the upright 25 supports 15, and has three filling compartments 16 each having a filling screw 17 therein operated by suitable mechanism (not shown).

Power is supplied to the apparatus 30 through the friction clutch pulley 18 and the shaft 19 carrying the worm 20 which meshes with the worm gear 21 upon the shaft 4. The worm shaft 19 also carries the bevel gear 22, from which the filling 35 screws 20^a may be operated (by connecting mechanism not shown). The shaft 19 also carries the bevel pinion 23 meshing with the bevel gear 24 on shaft 25, which in turn carries the miter gear 26 meshing with bevel 40 gear 27 on the cam shaft carrying the cams 28. The shaft 25 also carries a gear 29 meshing with the gear 30 on the shaft 31, and power is transmitted through this shaft and bevel gears 32 and 33 to the shaft 34 45 carrying the arms 35 arranged to act upon the cooled soap cakes to separate them from the pistons or plungers by which they are carried.

A series of operating cams or cam surfaces 50 adapted to act upon the rollers 12, are suitably supported a short distance from the series of molds. The cams or cam surfaces are arranged in series of three corresponding to the three series of molds, so that 55 the rollers of each series will be similarly and simultaneously acted upon. The cam segment 36 carrying the cam surfaces 36^a is supported by a transverse bracket 37 from the plate 38, which in turn is supported by 60 the upright supports 15 and 39. The angle irons 36^b of the cam segments 36 provide the flat surface for the rollers 12. Near its right end this cam segment has an outer surface 42 as well as an inner surface 41 thus 65 providing a groove 40 for the rollers and in-

suring that the rollers and the pistons operated thereby are properly positioned. This groove is inclined inwardly for reasons hereinafter explained. The cam section 43 is pivoted at 44 and adjustably supported at 70 45 by the adjustable support 46. This cam section likewise provides a double cam groove. The cam section 47 is of similar construction and is supported by an adjustable support 48. The cam section 49 is adjustably supported by the slide 50 operating in the guide 51, the adjustment being effected by adjusting screws 52 acting through the bell crank lever 53 and the connecting rod 54. The angle iron 55 which forms the 80 cam surface is pivoted at 57, and adjustable by means of slots 56 and bolts coöperating therewith. The cam surface formed by the member 55 is eccentrically arranged so that the lower right end thereof is somewhat 85 nearer to the cylindrical molds than is the upper left end, for reasons hereinafter explained.

The cam section 58 is of similar construction and arrangement. It is adjustable as 90 a whole by means of slide 60, and has its cam surfaces pivoted at 61 and adjustable by means of slots 62, so that the cam surfaces can be eccentrically arranged so that the lower end is somewhat nearer the cylindrical series of molds than is the upper end. 95

The cam section 63 is of similar construction and arrangement. It is carried by the slide support 64 and its outer cam surface 65 is pivoted at 66 and adjustable by means 100 of slots 67, so that it can be eccentrically arranged with its left hand end somewhat nearer to the cylindrical series of molds than its right hand end.

Arranged below the series of molds, to 105 the right of the soap container in Fig. 2, are spray pipes 68 for spraying the under surfaces of the mold with cold brine and thereby effecting a cooling of the soap therein. Above the molds but in the same 110 position is a cooling jacket 69 having a brine supply pipe 69^a and adapted for the flow of the cold brine therethrough over the inner plate 69^b which comes in contact with the outer surface of the soap in the molds and effects its preliminary cooling and incipient solidification. Arranged around the cylindrical series of molds is the endless roller belt 70 made up of links and cross arms 70^a carried thereby, said cross arms 115 each having track rollers 71 which are guided by a groove formed by the adjustable track angle irons 72 and 73, adjustable, e. g. as shown in Fig. 6. The endless roller belt 120 adjustable as a whole is carried by the sprocket wheels 75, 76, 77 and 78, except when the rollers are passing through the guide groove formed by the flanges 72 and 73. The sprocket wheel 76 is adjustable for taking up slack in the belt, and to this end 125 130

it is carried by an arm 79 pivoted at 80, and adjustable by means of the adjustable screws 81.

Carried by the cross rods 70^a of the endless roller belt are pistons or plungers 74 arranged to coact with the series of molds so that there is a piston or plunger for each mold.

Arranged at the upper left hand part of the apparatus shown in Figs. 1 and 3 is a slide 90 for receiving the cakes of soap separated from the pistons by the arms 35, and a spray pipe 91 is arranged for spraying brine or water upon the slide or upon the cakes as they are discharged. Arranged to the left of the soap container 13 in Figs. 1 and 3 is a transversely arranged belt 92 carrying brushes, said belt being supported by a bracket support 94, and driven in any suitable manner as by a belt 93. These brushes are arranged to remove any adhering soap from the outer surfaces of the cylindrical mold sections and from the pistons 10, which pistons, as shown, may project somewhat above the surrounding surfaces.

The cakes of soap discharged from the apparatus and passing down the slide 90 are received by the conveyer 96 which may be of screen material, and the cakes may then be passed through a further body of cold brine and subjected to a brine spray to effect their further cooling, although such further cooling may not be necessary, in which case the cakes may be passed directly to the wrapping and packaging apparatus after washing to remove any adhering brine and passing through the usual drier. If the cakes of soap are subjected to further cooling by means of the brine and are brought into direct contact with the brine they should thereafter be sprayed with fresh water to remove the brine, as more fully described in my said prior application, Serial No. 386,912.

The transverse belt brush 83 is similar to the brush 92, and is transversely arranged so that it will remove any adhering soap from the pistons or plungers of the roller belt. This belt scraper may be driven in any suitable way, as by means of belt 84.

Arranged beneath the filling mechanism, for receiving any soap that may escape around the pistons or otherwise, is a receptacle 82 which prevents any escaping soap from dropping into the brine. The soap thus collected can be scraped out from time to time and thereby recovered. With proper construction and fit of the pistons in the molds, and with proper operation of the apparatus, little if any escape into this receptacle should take place.

In the operation of the apparatus, the molten soap from the crutchers and compounded with the usual ingredients is introduced in the soap container 13 and is

maintained therein by the steam jacket at the proper temperature. The cylindrical series of molds is slowly and continually rotated by means of the worm 20 and worm gear 21, and the three series of molds are brought successively beneath the soap container. The pistons in each mold are kept flush with the surrounding surface of the mold sections, by the action of the double cam groove 40, upon the rollers 12, when the molds are first introduced beneath the soap container. As the molds pass beneath the compartments 16, the pistons are drawn downwardly by the rollers operating in the double cam groove of the cam section 43 and soap is simultaneously forced down into the molds by the action of the screws 17. The operation of the screws, and the lowering of the pistons, are so timed that the soap is forced downwardly into the molds at the same time that the pistons are drawn downwardly therein. The combined action results in the filling of the molds with the molten soap and with substantial avoidance of the occlusion or inclusion in the mold of air bubbles or air pockets.

As the filled molds are rotated beyond the soap container, they are subjected to the cooling action of the cold brine spray from the pipe 68 and to the cooling action of the cooling jacket 69, the spray acting upon the inner surfaces of the molds and the surface 69^b acting directly upon the outer surface of the soap in the molds. The soap is thus given a preliminary chill before the molds are immersed in the brine in the tank 1. As the molds pass downwardly beyond the lower end of the surface 69^b, the pistons or plungers 74 are brought into alignment with the molds, and each mold is thereby covered or closed by a piston or plunger. The guide flange 73 is so arranged as to bring the pistons 74 into registry with the molds and thereby close the molds as soon as the molds have been moved below the lower end of the cooling surface 69^b, and before the molds enter the brine.

The molds after being thus closed by the pistons or plungers 74 then pass down into the tank 1, the soap being protected from the direct contact with the brine, so that the brine acts indirectly through the inner and outer pistons and through the mold walls. The soap is thus rapidly cooled and the outer portions of the cakes are rapidly solidified.

The endless roller belt requires no separate driving mechanism, but it will be driven by engagement of the pistons or plungers 74 with the molds. The pistons may be thus very lightly tapered to facilitate their entrance into the molds, or the molds themselves may be slightly tapered at their outer ends.

As the soap is progressively cooled and

chilled by the brine, it will undergo an appreciable shrinkage. This is compensated for by the eccentric arrangement of the cam surfaces with which the rollers come into engagement. That is, by arranging these cam surfaces eccentrically and progressively nearer to the cylindrical series of molds, the inner pistons 10 will be progressively forced outward to an extent corresponding to the eccentricity. The grooves in which the rollers carrying the outer pistons 74 operate can likewise be arranged eccentrically and adjusted so that the outer pistons will be moved inwardly sufficiently to compensate for the shrinkage of the soap upon cooling.

After the preliminary cooling and shrinkage of the soap has taken place, and after the soap has reached a proper degree of solidity, it is then subjected to a pressing operation comparable with the pressing to which cakes of soap are commonly subjected, but this pressing operation is combined with the molding and cooling operation so that the entire molding, cooling and pressing operations take place in the same apparatus and without the necessity for subsequent operations thereafter. To this end, the angle irons 72 and 73 which form the guiding groove for the rollers 71 are given a greater degree of eccentricity, at the portion of the apparatus opposite the cam section 63, and the cam surfaces 65 of this cam section may likewise be given an increased degree of eccentricity so that either or both the inner and outer pistons or plungers will be forced into the molds to a sufficient extent to give the desired pressing to the soap therein.

It will be understood that the rate of movement of the cylindrical series of molds is such that the desired cooling action will take place, and such that the soap will be sufficiently solidified before and during the pressing operation, so that the cakes of soap when removed from the molds will not undergo any further appreciable shrinkage such as would cause deformation.

After the soap has thus been molded and pressed, the cakes are removed from the molds. The outer pistons are thus forced away from the molds by the arrangement of the outer left hand end of the inner guide surface 72. Then when the molds come into alignment with the cams 28, these cams act upon the rollers and pistons to force the cakes of soap out of the molds, and the cakes are then separated from the inner pistons by the arms 35. The operation of the cams 28 and of the arms 35 is so timed that the cakes will be properly and effectively removed from the molds and pistons. The cakes then pass down the slide 90, being assisted by the spray from the pipe 91, and

then pass on to the conveyer screen or belt 96.

After the cakes of soap have been removed from the molds the pistons are forced outwardly, by the action of the cam 36 upon the rollers, so that they project somewhat beyond the cylindrical surface of the mold sections, and any adhering soap is then brushed from the pistons and from the surface of the mold sections by the belt brush 92. Upon further rotation of the molds the pistons are drawn down even with the surrounding surfaces of the mold sections, by the action of the cam groove 40 upon the rollers, and the pistons are held in this position when the molds first pass beneath the soap container.

It will thus be seen that the position of the pistons in the molds is controlled by the various cam surfaces acting upon the rollers 12, and that the cam surfaces are adjustable to vary the action of the pistons. The pistons are thus forced outwardly, even with or slightly beyond the cylindrical surface of the mold sections, while the cakes of soap are being separated from the pistons by the arms 35, and while the pistons are being freed from adhering soap by the belt brush 92. The pistons are then kept flush with the surrounding cylindrical surface while the molds are being passed beneath the edge of the soap container. The pistons are then drawn inwardly simultaneously with the forcing of the soap into the molds by the screws 17, so that the molds are completely filled and the inclusion of air bubbles or pockets prevented. The eccentric arrangement of the cam surface 55 then causes the inner pistons to move outwardly, as the molds are being rotated, to compensate for the shrinkage of the cakes upon initial cooling. The cam surfaces 56 and 65 may also be given the desired degree of eccentricity to compensate for the shrinkage, and to assist in pressing the cooled cakes of soap. The outer pistons will simultaneously be forced into contact with the soap with the proper degree of pressure to give to the cakes the necessary pressing, until the complete cooling and pressing operation has taken place. After the completion of these operations, and upon further rotation of the molds, they are ultimately brought into alignment with the cams 28, and the cakes are forced outwardly and separated from the molds and pistons, after which the operation is repeated. The inner and outer pistons will be freed from any adhering soap prior to the beginning of the next operation by the action of the belt brushes 92 and 83. The thickness of the cakes of soap can be varied without changing the structure of the apparatus by adjusting either the inner cam surfaces so

as to vary the positions of the inner pistons in the molds during the operation, or by similarly adjusting the guide groove of the outer pistons to effect the same end. A 5 thinner or a thicker cake of soap can thus be produced. It will be understood that the three cam surfaces or the three series of molds can be simultaneously adjusted so that the pistons of any three corresponding molds will be operated simultaneously 10 in the same way.

The brine employed can be kept at the proper temperature by any suitable cooling means, for example, by the use of ammonia 15 refrigeration apparatus. Brine may thus be cooled to a temperature of around 5 to 15° F., so that an energetic cooling action will take place. With this temperature, it requires but a few minutes to effect the 20 necessary molding and cooling of the soap cakes. As a result, the apparatus can be operated in a relatively rapid and continuous manner, so that it will have a large capacity.

25 It will be evident that the molds may be of different sizes and shapes, for example, such that the resulting cake will be of oval, round, square, rectangular or other shape by properly designing the individual molds 30 and pistons.

Inasmuch as certain materials are corroded by the action of the brine, the apparatus should be constructed of material which is not acted upon, or, if constructed 35 of materials which are so acted upon, the apparatus should be enameled or otherwise protected from corrosion. The parts of the apparatus which are immersed in the brine may thus be coated with enamel, or 40 they may be made of materials which require no protection against corrosion.

45 Soaps of different character can be molded and cooled in the apparatus and according to the process of the present invention. The soap may thus be "floating" soap of high purity, or it may be laundry or other soap containing other detergent ingredients in admixture with the soap. The soap, prior to molding and cooling, is 50 subjected to the usual preliminary treatments, well understood in the art. The soap, after such preliminary treatments, and while still molten, is brought to the soap container at a temperature of around 150 55 to 175° F. and charged into the molds at approximately the same temperature.

It will be understood that the surface of the pistons which effect the pressing of the soap in the molds may vary in the shape of 60 its pressing surface. Thus, for example, the surface of either or both pistons may be depressed so that the resulting cakes of soap will be oval in shape. Similarly cakes of rectangular or other shape may be made.

So also, the cakes of soap may be given 65 the usual labels or marks, as will be readily understood.

It is an important and characteristic advantage of the present invention that the soap is rapidly converted from a molten 70 liquid state to the form of molded, cooled and pressed cakes ready for wrapping and packaging. The present invention thus makes unnecessary the provision of separate pressing mechanism, and the apparatus of 75 the present invention, therefore, requires but a comparatively small space for its operation. The present invention thus enables an important economy to be obtained both in the time required for the conversion of 80 molten soap into the final soap cake, and in the apparatus and space required for such conversion.

While the apparatus illustrated and described has three series of molds, it will be 85 understood that the apparatus can be constructed and operated in a similar manner with a larger or smaller number of series. So, also, the specific construction illustrated and described can be varied without departing 90 from the spirit and scope of the invention.

I claim:

1. The method of molding, cooling and pressing soap, in order to convert the soap 95 into the form of compressed cakes, which comprises charging the molten soap into molds for the individual cakes of soap, passing the molds through cold brine without direct contact of the brine with the soap, 100 subjecting the soap while in the molds to a sufficient degree of cooling to effect solidification, and to a sufficient degree of pressure to effect the pressing of the cooled soap, the cooling and pressing operations being 105 so regulated as to give a cooled and pressed cake of soap, and removing the cake of soap thus produced from the molds.

2. The method of molding, cooling and pressing soap, in order to convert the soap 110 into the form of compressed cakes, which comprises charging the molten soap into molds for the individual cakes of soap, between oppositely acting pistons, passing the molds through cold brine without direct contact of the brine with the soap, subjecting the cakes of soap to pressure between 115 said pistons while being cooled, and to a sufficient degree of pressure after cooling to convert the soap into the form of pressed 120 cakes, and removing the resulting cakes of soap from the molds.

3. An apparatus for molding, cooling and pressing soap, comprising a series of molds arranged to pass through a cooling liquor, 125 means for protecting the soap from direct contact with the liquid while passing therethrough, and means for subjecting the

6
soap while in the molds to a sufficient degree of pressure to convert the soap into the form of cooled, pressed cakes.

4. An apparatus for molding, cooling and 5
pressing soap, comprising a series of molds, upper and lower pistons arranged to compress the soap in such molds, means for passing the molds and pistons through a cooling liquor, and means for subjecting the 10
soap in the molds to a sufficient degree of pressure between such pistons to convert the soap into cooled, pressed cakes.

5. An apparatus for cooling, molding and 15
pressing soap, comprising a series of molds cylindrically arranged, means for filling the molds with molten soap, means for conveying the molds through a cooling liquid, and pistons arranged to close the molds and adapted to subject the soap therein to a sufficient 20
degree of pressure to convert the soap into the form of cooled, pressed cakes.

6. An apparatus for molding, cooling and 25
pressing soap, comprising a cylindrically arranged series of molds, means for filling said molds with molten soap, a series of pistons arranged to close said molds and to pass therewith through a receptacle containing a cooling liquid and to subject the soap to pressure, and means for ejecting the cakes 30
of cooled, pressed soap from the molds.

7. An apparatus for molding, cooling and 35
pressing soap, comprising a tank containing a cooling liquid, a cylindrically arranged series of molds rotatable therein, means for filling the molds with molten soap, and an endless belt carrying a series of pistons and so arranged that the pistons will close the molds and pass through the cooling liquid as the molds rotate therein, and means for forcing said pistons into the molds to subject 40
the soap to pressure therein, and means for discharging the cooled and pressed cakes of soap from the molds.

8. An apparatus for molding, cooling and 45
pressing soap, comprising a receptacle for a cooling liquid, a cylindrically arranged series of molds rotatable therein, each mold having a piston therein, means for filling the molds with molten soap, an outer series of pistons carried by the endless belt and arranged to close the molds and rotate therewith through the cooling liquid, and means for acting upon said inner and outer pistons to subject the soap in the molds to pressure, whereby the soap is converted into the form 50
of cooled and pressed cakes, and means for removing the resulting cakes from the molds.

In testimony whereof I affix my signature.
CECIL O. PHILLIPS.
